UNITED STATES PATENT OFFICE

2,158,453

CHAIR

Glenn D. Wood, Elkhart, Ind., assignor to Posture Research Corporation, Elkhart, Ind., a corporation of Indiana

Application February 18, 1937, Serial No. 126,387

1 Claim. (Cl. 155—163)

This invention relates to improvements in chairs and it consists of the matters hereinafter described and more particularly pointed out in the appended claim.

5 The chair with which the present invention is more particularly concerned, is one wherein the back rest is adjustably and pivotally mounted with respect to the seat and a brace is employed between the back rest and the seat. Such a 10 chair is exemplified in my prior Patent 2,018,825 of October 29, 1935. In the chair of said patent, the front end of the brace is operatively connected to an elongated member at one side of the seat or its supporting frame, by means of 15 a bolt passing through said brace end and through one of a number of longitudinally spaced holes in said elongated member. When it is desired to adjust the angular position of the back rest, it is necessary to completely remove the bolt 20 from said elongated member and then replace it in that opening providing the desired adjustment. Such adjustments are not always made by experienced persons so that difficulty is encountered in lining up the bolts with the proper holes. Also, 25 by reason of the spacing between the holes, the desired adjustment can only be approximated.

One of the objects of the present invention is to provide in a chair of this kind, a novel connection for the brace with respect to the seat, 30 wherein an accurate back rest adjustment may be more readily made without a complete removal of the retaining bolts connecting the brace to the seat.

A further object of the invention is to provide 35 in a chair of this kind, a novel connection for the brace arm with the seat flange and which connection, when loosened, may be slid in guided engagement along the side of the seat into the desired adjusted position, merely by moving the back rest into the desired angular position with 40 respect to the seat.

Another object of the invention is to provide 45 in a chair of this kind, a slidable connection for the brace arm with the seat and which connection may be locked positively against movement induced by a pressure imposed in one direction or the other, upon the back rest.

The above mentioned objects of the invention, as well as others, together with the several advantages thereof, will more fully appear as the 50 specification proceeds.

In the drawing:

Fig. 1 is a view in side elevation of the seat and backrest of an adjustable back rest chair embodying the preferred form of the invention.

Fig. 2 is a horizontal sectional view through one side of the chair, on an enlarged scale, as taken on the line 2—2 of Fig. 1.

Fig. 3 is a vertical detail sectional view through a part of the chair as taken on the line 3—3 of Fig. 2.

Fig. 4 is a perspective of a certain runner block, embodied in the improved chair construction.

Referring now in detail to that embodiment of the invention illustrated in the drawing: 5 indicates the seat of the improved chair and 6 indicates the back rest of the chair, both of which are shown herein as upholstered. While this is not essential, it is preferable.

The seat is supported upon a spider 7 which is 15 operatively mounted on a seat post 8 having a rotative bearing engagement in a conventional chair base, not shown herein. The spider is provided at each of its opposite sides with an edge-wise disposed elongated or flange-like element 9 20 which may or may not be formed as an integral part of the spider. As shown herein, said member is formed as the vertical flange of an angle bar, the horizontal flange 10 of which faces inwardly and rests upon and is secured to the associated part of the spider. In each elongated member 9 is a longitudinal slot 11 and on the inner face of each of said members are vertically extending V shaped ribs and grooves 12.

Associated with the inner face of each elongated member 9 is a runner 13. As shown in Fig. 4, said runner is in the form of a block having longitudinally spaced guide lugs 14 projecting from one face of the block for engagement in the slot 11. On said face of the runner, 30 above and below said lugs, are vertically extending V shaped ribs and grooves 15. The ribs on the runners engage in the grooves 12 on the elongated member and the ribs on the latter engage in the grooves on the runners. In said 40 runner 13, at a point between the lugs 14 is a threaded hole 16.

The back rest 6 is disposed between the top ends of a pair of downwardly and forwardly curved arms 17. A screw 18 carried by the top 45 end of each arm is operatively engaged with the back rest to provide a connection therebetween. A plurality of longitudinally spaced holes 19 is formed in the bottom end of each arm and a screw 20 passes through one of said holes and 50 is threaded into a hole in the associated elongated member 9 to provide a pivotal connection for each arm with respect to the seat. At a point midway between the ends of each arm is a plurality of holes 21, arranged in a row ex- 55

tending transversely of the arm. The purpose of said holes will soon appear.

Associated with each back rest supporting arm, is a brace 22, the top end of which is connected 6 to an associated arm 17 by a screw 23 threaded into one of the holes 21. The other end of each brace is disposed to the outside of the associated member 9. A screw or bolt 24 passes through said end of each brace and through the slot 11 10 in the associated elongated member 9 for a threaded engagement in the hole 16 in a runner 13. A spacing washer 25 is securely positioned on the bolt 24 between said elongated member and the associated end of the brace, 15 and a second washer 26 is positioned on said bolt between the said brace end and the head of the bolt. This arrangement swivels the bolt 24 with respect to brace end. If desired, the brace 22 may be a yielding telescopic one such as is illustrated in the before mentioned patent, but the 20 use of such a brace is not essential in this particular instance.

When the bolt 24 is tightened, due to its swivelled connection with the brace end, it threads 25 into the runner and draws the same toward the elongated member 9 so that the ribs 15 on the block fit snugly in the grooves in said elongated member and vice-versa. Thus, the runner is positively held against longitudinal movement 30 with respect to the elongated member. To adjust the forward or backward position of the back rest with respect to the seat, the bolts 24 are loosened. As each bolt is thus loosened, it causes a lateral separation between the runner 35 and the associated brace 22. By a forward or rearward pressure on the back rest, according to the position into which it is to be adjusted, the brace arms 22 will slide the runners 13-13 along the members 9 into the desired position, the ribs and grooves 15 of the runners clicking 40 over the grooves and ribs 12 of the members 9. It is pointed out at this time, that the lugs 14 are of a depth greater than that of the ribs and grooves on the runner. Thus, when the bolts 24 are loosened, previous to making a back rest adjustment, said lugs remain in the slots 12 for 45 guided engagement, after a separation of the ribs and grooves of the runners with those of the members 9.

When the back rest has been adjusted to the 50

desired position, the bolts 24 are tightened up and this draws the runners 13 toward their elongated members 9 so that the respective ribs and grooves thereof engage as before to positively lock the runners in place against longitudinal 5 movement.

It is apparent, from the above, that it is not necessary to completely remove the bolts 24 in making a back rest adjustment, but that such an adjustment is afforded merely by loosening 10 said bolts and then swinging the back rest into the desired adjusted position. Thereafter, the bolts are tightened to lock the back rest in the desired adjusted position.

While in describing the invention I have referred in detail to the form, arrangement and construction of the various parts involved, the same is to be considered only in the illustrative sense so that I do not wish to be limited thereto except as may be specifically set forth in the 20 appended claim.

I claim as my invention:

A chair embodying therein a seat, a flange-like member along each side of the seat and having a longitudinal slot therein and having transverse 25 ribs and grooves on the inner face thereof above and below said slot, a back rest, supporting arms therefor, one on each side of the seat and each having a pivotal connection at one end with a flange-like member along the associated side of 30 the seat, a runner for each flange-like member and having a screw threaded opening therein and also having complementary grooves and ribs for engagement with those on the associated flange-like member, a brace at each side of the 35 seat and having a pivotal connection at one end with an associated back rest supporting arm, spaced lugs on each runner, one on each side of the opening therein and adapted for engagement in the slot of the associated flange-like member, and a threaded member carried by the other 40 end of each brace, extending through the slot in said flange-like member and threaded into the opening in the runner engaged with said flange-like member, said lugs having a depth greater 45 than the depth of the said ribs and grooves to prevent a turning of said runner when said threaded member is turned.

GLENN D. WOOD.
